BALANCED, PLUG TYPE, THROTTLE VALVE

Filed Jan. 16, 1933

Inventor
Frank Henneböhle

By *Albert E. Dieterich*

Attorney

partition dividing the inlet from the outlet, said partition having a frusto-conical valve seat surface and having diametrically opposite ports, a tubular frusto-conical valve proper located in said casing on said seat and having diametrically opposite ports to register with those of said partition, the larger end of said valve proper being constantly in communication with the inlet side of the valve casing, said valve casing having a packed neck and said valve proper having a stem projecting through said neck, said valve proper having its smaller end closed save for a small port passing through the same and having an end-thrust surface of lesser diameter than the end of the valve, said casing having an end-thrust bearing surface engaged by said end-thrust surface, and said end-thrust surface being so related to the area of the frusto-conical valve seat surface that wear on each will approximately balance so that contact between said respective surfaces will always be maintained, and the valve proper will be held against sticking, and means to prevent the valve proper being unseated when fluid pressure within the valve is absent.

2. A plug-type throttle valve, comprising a casing having an inlet and an outlet, and having a partition dividing the inlet from the outlet, said partition having a frusto-conical valve seat surface and having diametrically opposite ports, a tubular frusto-conical valve proper located in said casing on said seat and having diametrically opposite ports to register with those of said partition, the larger end of said valve proper being constantly in communication with the inlet side of the valve casing, said valve casing having a packed neck and said valve proper having a stem projecting through said neck, said valve proper having its smaller end closed save for a small port passing through the same and having an end-thrust surface of lesser diameter than the end of the valve, said casing having an end-thrust bearing surface engaged by said end-thrust surface, and said end-thrust surface being so related to the area of the frusto-conical valve seat surface that wear on each will approximately balance so that contact between said respective surfaces will always be maintained, and the valve proper will be held against sticking, and means to prevent the valve proper being unseated when fluid pressure within the valve is absent.
